UNITED STATES PATENT OFFICE.

FRANK A. HOWARD, OF ELIZABETH, NEW JERSEY, ASSIGNOR TO STANDARD OIL DEVELOPMENT COMPANY, A CORPORATION OF DELAWARE.

ART OF OBTAINING LIGHTER PRODUCTS FROM HYDROCARBONS.

Application filed August 16, 1922. Serial No. 582,114.

The present invention relates to the art of obtaining lighter products from hydrocarbon oils by distillation or cracking, and will be fully understood from the following 5 description taken in connection with the accompanying drawings, in which—

Fig. 1 is a perspective view of one form of apparatus contemplated in my invention, parts being broken away for clearness; and 10 Figs. 2, 3 and 4 are enlarged detail sections taken on the lines 2—2, 3—3 and 4—4 respectively, of Fig. 1, looking in the direction of the arrows.

Referring first to Fig. 1, the numeral 1 15 designates a furnace setting arranged to be fired by a suitable fuel, for example oil, and heating a bath 2 of molten lead or alloys or material which is analogously fluid at temperatures up to 900° F. A still 3 containing oil is placed in the molten bath and is arranged with disengageable connections, and moving means so that it can be taken out when necessary, for cleaning, and be replaced by a freshly-charged still. Traveling 20 on suitable overhead rails 4 is a carriage comprising a framing 5 supported on flanged wheels 6 (of which there may be two at each end) having shafts geared to be driven from a motor 7 carried in the frame, so 25 as to enable movement of the carriage as desired from positions over the still to positions over cleaning and charging station supports beyond the furnace setting. Mounted on suitable bearings, for instance of ball 30 or cone type, are worm gear wheels 8 meshing with a worm-shaft 9 which is geared from a driving motor 10. The gear wheels 8 are internally threaded or nut-threaded to engage with vertical stem-shafts 11 which 35 are splined, or for example shaped somewhat hexagonally in cross section and correspondingly threaded on two opposite faces and mounted to slide on their smooth faces in slide-bearings in the carriage, and carry at 40 their lower ends a platform 12. A pair of longitudinal shafts 13 is mounted in bearings on the platform 12 and geared to rock together, by means of segment gears 14. On the projecting end of one of the shafts 13 45 is a worm wheel 16 and meshing therewith is an actuating worm shaft 17 which may be rotated, as required, by a hand-wheel 18. Fixed to the shafts 13 are arms 19 having extremities shaped for engaging notches N in 50 projections 20 on the top of the still. These

projections may have shoulders 21 which support a cover 22 of heat insulating material suitably strengthened and reinforced, and adapted to seat down against and form a top cover element for the still-heating 60 chamber in the instances where a cover is desired. The shafts 13 with arms 19, etc., it will be noticed form a mechanism actuated by hand-wheel 18 by which the still can be gripped to the carriage for moving when 65 desired.

Arranged on the projections 20 are recesses 23 to receive the ends of arms 24 which are fixed on and swung by the shafts 25 70 supported in bearings on the I beams 26, the shafts 25 being in turn actuated through worm gearing 27 and the hand-wheel-operated vertical shaft 28' and being geared to turn together by bevel gear wheels 25' and 75 suitable intermediate cross-shafting.

The vapor-pipe 29 from the still has a flange joint 30, which advantageously is of the quick detachable type, and leads through a double elbow, for adjustment, to a vapor-line manifold 33 and a suitable condenser system, not shown for simplification. A pipe 34 is also provided in which the still pressure (in instances where operating under pressure) may be released when required as 80 a preliminary to disconnecting. Suitable valves 32 and 35 are arranged for shut-off use and the connection onto the still may advantageously embody a cut-off valve, such for instance as the outer valve member 31 85 fitting by a slight taper on the inner valve member 36 fixed to the still-dome 37 and having ports alining when the still is in operating position, but closed off when the pipe 29 is turned somewhat downwardly. 90 A nut 39 and washer serves to hold the valve members in snug working relation. Where preferred, this type of automatic valve may be substituted by a simple hand-operated valve in the pipe. 95

An operating platform or cage 34' is suspended from the overhead carriage and contains the controlling rheostats R for the carriage motor 7 and lifting motor 10 and a brake-lever B linked to a suitable brake on the driving shaft of wheels 6. The hand wheels 18 and 28 for gripper-arms and the locking-arms respectively are in convenient reach when to be used, as it will be noticed that there is no occasion to change the 100 105 110

gripper-arms during the time their actuating wheel 18 happens to be in elevated position between the struts of the carriage frame.

To prevent damage from over-run by the 5 stem-shafts 11, circuit-breakers are provided, the boxes being placed in the operating cage to permit manual re-setting of the switch, and the contact-tappets T being attached at the proper points on shaft 11 and positions 10 cooperating therewith.

In operation, the furnace being fired and the molten bath brought to the desired temperature, a still or container charged with oil while resting on the supports at the cleaning 15 and charging station is picked up and transferred to the molten bath by the overhead carriage. To do this, the attendant operates the driving motor 7 by its controller rheostat in the operating cage 34' so as to bring the 20 carriage to the overhead registry point, then operates the motor 10 by its controller rheostat so as to rotate the shaft 9 and turn the nut-gears 8 to lower the stem-shafts and the gripper-arms 19 supported therefrom, 25 into reach of the projections 20 on top of the still; he then turns the hand-wheel 18 to actuate the worm-gearing and the shafts to swing the gripper-arms 19 into holding engagement in the notches, and again operates the driving motor to bring the carriage to the overhead registry point for the 30 furnace, lowers the still or container by motor 10 sufficiently to permit connecting up the joint 30, then opens the valve 32 and lowers the still into final position, the valve 31 being automatically opened by the movement. The operator then turns the locking arms 24 down into position, against the standards 20 on the still, by hand-wheel 28, raises the 35 shafts 11 by motor 10, and withdraws the carriage. In case a hand-operated valve be used instead of the automatic valve 31, the vapor-pipe 29 must be connected up at the joint 30 after placing the still; and the valve 40 32 is finally opened. The distillation or cracking is proceeded with, the vapors passing over to the condenser system, and pressure will be used or not, as appropriate. In 45 conducting a cracking operation on some stocks I contemplate a pressure as high as 50 350 lbs. or more for example.

When the still contents have been reduced to the point desired, and in some cases, where the stock admits, I contemplate running the charge to dryness, the valve 32 is shut and valve 35 is opened to release the pressure into the release line. In the instances of distillation without pressure the valve 35 of course need not be used. The 55 carriage is then brought into position and the still is engaged and lifted sufficiently to shut, if it had been open, the automatic valve 31. Valve 35 is then shut and the joint 30 disconnected and the still is raised on 60 up and carried away to the cleaning and 65

charging station and a freshly-charged still is brought in and put into operation, etc.

The stills are of course equipped as usual with temperature and pressure indicating instruments, safety valves, and connections 70 for feed and withdrawal of oil, etc.

Although a one-still installation may be worked satisfactorily, the still at the completion of its run being taken out and replaced by a fresh still, it is more advantageous to have the installation large enough 75 to include more than one still at a time, the units being charged and replaced in regular rotation.

While I have described my invention with 80 reference to certain specific details, it will be understood that this is for the purpose of illustration rather than limitation, and the invention is limited only as defined in the 85 following claims, in which it is my intention to claim all inherent novelty as broadly as the prior art permits.

What I claim is:

1. A systematic method of heat treating 90 hydrocarbon oil, comprising contacting a distillation vessel containing the oil with a molten material maintained at a high temperature, collecting the distillate and breaking said contact of distillation vessel with said molten material as soon as the distillation is substantially completed.

2. A systematic method of cracking hydrocarbon oil, comprising contacting in rotation a plurality of distillation vessels containing the hydrocarbon oil, with a molten bath maintained at a high temperature, collecting the vapors evolved, and breaking 100 said contact as soon as the evolution of vapors is substantially complete.

3. A systematic method for cracking hydrocarbon oils in a cycle of successive operations, comprising charging the hydrocarbon oil into a plurality of distillation vessels, contacting said vessels in rotation with a molten bath maintained at a high temperature, collecting distillate, breaking said contact as soon as the distillation is substantially complete, cleaning said vessels and recharging the same with hydrocarbon oil 110 in rotation.

4. Apparatus of the character described, which comprises a container for a material which is liquid when heated, a receptacle for holding oil adapted to be removably placed in said container, means for holding the receptacle largely submerged in the liquid and means on said receptacle whereby the receptacle can be engaged to be lifted out. 115

5. Apparatus of the character described, which comprises a lead bath, a furnace for heating said lead bath, a plurality of stills adapted to be removably placed in said lead bath, a vapor off-take pipe for each still, a detachable joint in each said pipe, locking-arms adapted to hold the stills in position 120 125 130

in the lead bath, actuating means for said locking arms, gripping arms adapted to grip the stills, actuating means for said gripping arms, stem-shafts for bodily raising and 5 lowering said gripping arms, a carriage supporting the stem-shafts and means for laterally moving the carriage.

6. Apparatus of the character described, which comprises a furnace, a heat-transmitting medium adapted to be heated and 10 maintained in a liquid state thereby, a still

adapted to be removably placed in said heat-transmitting medium, a vapor off-take pipe, a detachable joint in said pipe, a shut-off valve on each side of the joint, means for holding the still in position in the heat-transmitting medium such that a large part of the still is submerged, and means for moving the still into or out of the heat-transmitting medium.

15

FRANK A. HOWARD.
